CLAIM

The ornamental design for a toy cube, as shown and described.

DESCRIPTION

FIG. 1 is a front, right-side, and top perspective view of a toy cube showing my new design;

FIG. 2 is rear, left-side and bottom perspective view thereof; and,

FIG. 3 is a front view thereof.

The rear view, right-side view, left-side view, top view, and bottom view thereof are identical to the front view.
